(57) **CLAIM**

The ornamental design for a remote control unit, as shown.

DESCRIPTION

FIG. 1 is a front view of the remote control unit of the
present invention;

FIG. 2 is a side view of the remote control unit;

FIG. 3 is a side view of the remote control unit;

FIG. 4 is a top view of the remote control unit; and,

FIG. 5 is a bottom view of the remote control unit.

The broken lines in the Figures are for illustrative purposes
only and form no part of the claimed design.
